(57) **CLAIM**

The ornamental design for amplified speakers with alarm clock, as shown and described.

DESCRIPTION

FIG. 1 is a top, front, right side perspective view of a amplified speaker with alarm clock showing my new design; FIG. 2 is a perspective view of FIG. 1, without the portable device.

FIG. 3 is a top plan view thereof;

FIG. 4 is a front elevational view thereof;

FIG. 5 is a rear elevational view thereof;

FIG. 6 is left side elevational view thereof;

FIG. 7 is a right side elevational view thereof;

FIG. 8 is a bottom plan view thereof;

FIG. 9 is a top, front, right side perspective view of FIG. 1, in an alternate condition;

FIG. 10 is a top plan view thereof;

FIG. 11 is a front elevational view thereof;

FIG. 12 is a rear elevational view thereof;

FIG. 13 is left side elevational view thereof;

FIG. 14 is a right side elevational view thereof; and,

FIG. 15 is a bottom plan view thereof.

Broken lines depict environmental material that is not part of the claimed design.
